UNITED STATES PATENT OFFICE.

TELESPHORE BABIN, OF HOUMA, LOUISIANA.

SINK.

Application filed June 24, 1921. Serial No. 480,036.

To all whom it may concern:

Be it known that I, TELESPHORE BABIN, a citizen of the United States, residing at Houma, in the parish of Terrebonne, State of Louisiana, have invented a new and useful Sink; and I do hereby declare the following to be a full, clear, and exact description of the invention, such as will enable others skilled in the art to which it appertains to make and use the same.

The invention relates to sinks, and has for its object to provide a device of this character, which is formed from a single sheet of metal bent to form bottom, end, front and rear walls, and which rear wall is provided with an upwardly extending portion forming a splash member.

A further object is to provide the upper ends of the end and front walls of the sink with rolls, thereby reinforcing said walls and to secure the end walls of the rear wall by providing the rolls of the end walls with extensions disposed in apertures in the rear wall and which extensions engage the rear side of the rear wall, thereby rigidly securing the end wall to the rear wall.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:—

Figure 1 is a front elevation of the sink, parts being broken away to show the structure.

Figure 2 is a top plan view of the sink, parts being broken away to show the structure.

Figure 3 is a transverse vertical sectional view through the sink.

Referring to the drawings, the numeral 1 designates a pair of spaced supporting brackets and 2 the sink supported thereby. The sink 2 comprises a rectangular shaped horizontally disposed body portion 3 and the vertically disposed back 4, which back serves to prevent splashing of the water on the wall when the sink is in use. The

bottom 5 of the body portion 3 is inclined as shown in Figure 1 so that the water will drain from the sink. The bottom 2 adjacent one side of the sink is provided with an annular flange 6, to which flange is secured in any suitable manner a downwardly extending annular sleeve 7, the bottom of which sleeve is closed by the conically shaped bottom 8, the annular flange 9 of which receives the lower end of the sleeve 7. Flange 9 is secured to the sleeve 7 in any suitable manner for forming a watertight joint. The conically shaped bottom 8 terminates in a downwardly extending tubular section 10 which tubular section telescopically engages the upper end 11 of a waste pipe 12. The tubular extension 10 is provided with a rubber plug 13, which plug when in position allows the accumulation of water within the auxiliary chamber 14, thereby allowing a limited amount of hot water to be used and sufficient depth of water to be obtained without filling the main chamber 15 of the sink, which would require a great deal of water. If so desired the auxiliary chamber 14 may be filled with water and dishes washed therein, then deposited on the inclined bottom 5 of the sink, thereby allowing the water from the dishes to drain back into the chamber 14. It will be seen that by so constructing the sink the use of the drain board is obviated.

The sink as a whole may be cast in one piece or stamped from metal in one piece. However it is preferably built up of sheet metal with reinforcing ribs 16, the ends 17 of which are riveted at 18 in the back 4, thereby additionally bracing the sink and forming a rigid structure.

It will be seen that by providing the reinforcing ribs on the end walls and riveting the ends thereof at 18 to the rear wall, the rear wall will be securely bound to the side walls and the side walls braced by said connection.

The invention having been set forth what is claimed as new and useful is:—

A sink formed from sheet metal, the body of said sink being formed from a single sheet of metal bent to form end walls, front and rear walls, the rear wall extending upwardly above the upper side of the sink,

thereby forming a splash member, the upper edges of said walls being provided with reinforcing rolls, the rear ends of the rolls of the end walls extending through the rear wall and overlying the rear side of the rear wall.

In testimony whereof I have signed my

name to this specification in the presence of two subscribing witnesses.

TELESPHORE BABIN.
